UNITED STATES PATENT OFFICE.

NICHOLAS STEFFENS, OF NEW YORK, N. Y.

DESIGN FOR A FLOWER-FRAME.

SPECIFICATION forming part of Design No. 20,583, dated February 24, 1891.

Application filed January 31, 1891. Serial No. 379,821. Term of patent 7 years.

To all whom it may concern:

Be it known that I, NICHOLAS STEFFENS, a citizen of the United States, residing at the city of New York, in the county and State of New York, have invented and produced a new and original Design for Flower-Frames, of which the following is a specification, reference being had to the accompanying drawing, forming a part thereof, which represents a perspective view of a frame embodying my design.

The leading feature of the design consists of a base figure A, simulating a box-like struct-

ure, an arch-like figure apparently supported by the base figure, and a turnstile figure C within the arch.

The minor features of the design consist of a star figure a, located above the arch, and the representation of a keystone b in the arch.

I claim—

The design for a flower-frame, substantially as herein shown and described.

NICHOLAS STEFFENS.
